UNITED STATES PATENT OFFICE.

GEORGE WILLIAM THOMAS, OF WILLIAMSTOWN BEACH, VICTORIA, AUSTRALIA.

SHIP CONSTRUCTION.

Application filed May 8, 1918. Serial No. 233,356.

To all whom it may concern:

Be it known that I, GEORGE WILLIAM THOMAS, a subject of the King of Great Britain, residing at Williamstown Beach, 5 Victoria, Australia, have invented certain new and useful Improvements in Ship Constructions; and I do hereby declare the following to be a full, clear, and exact description of the invention, such as will enable 10 others skilled in the art to which it appertains to make and use the same.

This invention relates to ship construction and the primary object of the invention is to provide a nonsinkable ship or a ship, the 15 hull of which is constructed so that the ship will remain afloat in case the portion of the hull which is submerged in the water is punctured by a torpedo, shell or by contact with a reef or any other object which might 20 have a tendency to puncture the hull.

More specifically, the object of this invention is to provide a ship, the hull of which is composed of three sections which are arranged so that two of the sections will lie 25 parallel to each other and have their inner facing sides slightly spaced while the third section extends downwardly beneath the bottom of the side or upper sections and is substantially V-shaped in cross sections, to 30 provide a hollow keel for the vessel.

A further object of this invention is to provide a plurality of air retaining chambers formed along the bottoms of the two parallel sections and along the sides of the 35 lower substantially V-shaped section to increase the buoyancy of the boat or ship and to arrange the parallel sections so as to bring all the floating power to bear with the surface of the water, and to have sufficient load 40 carrying floating power to be capable of carrying the center or lower section which is built under the two side or parallel sections, thereby further decreasing the liability of the sinking of the ship in case the 45 third or center lower section is punctured.

With the foregoing and other objects in view this invention consists in such novel features of construction combination and arrangement of parts as will be hereinafter 50 more fully described illustrated in the accompanying drawings and claimed.

In describing the invention in detail, reference will be had to the accompanying drawings wherein like characters designate

like and corresponding parts throughout 55 the several views and in which:

Figure 1 is a side elevation of the improved ship having a portion thereof broken away to show the center section in section and a portion of one of the upper side or 60 parallel sections in section, and

Figure 2 is a vertical cross section through the three sections of the ship showing them in their arranged relation.

Referring more particularly to the drawings, 1 and 2 designate the upper parallel sections and 3 indicates the lower central section which is positioned between the two upper sections.

The hulls 1 and 2 are identical in construction, having their facing inner sides raised to form a space 4 through which the lower central section 3 may project to be loaded. A suitable closure 5 is provided for closing the lower portion of the space 4 and 70 this hatch is constructed of a plurality of connected chambers 6 in which are mounted air retaining pipes or reservoirs 7. The lower end of the closure 5 flares outwardly as shown at 8 so that in case the lower section 3 becomes filled with water, the upward pressure of the water will firmly seat 75 the closure 5 and form a fluid tight joint for the opening 4 so as to prevent water from passing out of the lower section 3 upwardly into the space 4.

The sections 1 and 2 are substantially of the usual construction or shape, being provided with partitions or bulk heads 9 which divide them into compartments or rooms and 80 they may have any desired number of decks 10.

The bottom of each of the sections 1 and 2 is composed of a plurality of layers of connected chambers 11 in which are positioned air retaining pipes or reservoirs to balance the sections 1 and 2 and cause the floating power or buoyancy of the boat to bear upon the surface of the water and also to provide sufficient buoyancy to be capable 95 of carrying or supporting the lower central section 3 in case the buoyancy of said section is destroyed by the puncturing thereof or the filling of the section with water.

The lower section 3 is substantially V- 100 shaped in cross section, to provide substantially a hollow keel for the entire ship structure and the sides of the lower section are

- composed of spaced plates 15 and 16 between which are positioned a plurality of air retaining reservoirs 17. The top or upper side of the section 3 is shaped to provide supporting members 18 which engage and lie in facial abutment with the outer surfaces of the bottom of the sections 1 and 2 as clearly shown in Figure 2 of the drawings. The top 18 is provided with an upwardly extending flue like extension 20 formed intermediate its ends which fit in the space 4 and the outer edges of the top 18 may be shaped as shown at 21 to snugly fit the lower outer edges of the sections 1 and 2.
- 15 The lower middle section 3 may be provided with suitable partitions or bulk heads 22 to divide the same into rooms or compartments 23, and it is desirable to mount the engines or propelling prime movers of the 20 ship in this portion of the ship.

In reducing the invention to practice, certain minor features of construction combination and arrangement of parts may necessitate alterations to which the patentee is 25 entitled provided such alterations are comprehended within the scope of what is claimed.

What is claimed is:

A ship comprising a keel portion consist-

ing of inner and outer plates substantially 30 V-shape in cross section, the inner plate extending inwardly from opposite sides to provide a space and supporting members overlapping the space, said inner plate having spaced vertical walls extending at a right 35 angle to said supporting members, the outer plate having its terminals extending outwardly in the opposite direction to said supporting members to form second supporting members, hull sections disposed on said 40 supporting members and in contact with said vertical walls, the second supporting members being deflected upwardly to overlap the outer sides of said hull sections, a closure means operable in said space and being of a 45 width greater than the distance between said walls and being buoyant so as to wedge between said walls under urgency of inrushing water, and said hull sections each having float means in the bases thereof to function to sustain the ship should water enter 50 said space.

In testimony whereof I affix my signature in presence of two witnesses.

GEORGE WILLIAM THOMAS.
